UNITED STATES PATENT OFFICE.

CARL C. GULDBECH, OF BEACON, NEW YORK.

DRIVING MECHANISM FOR MIXING MACHINES.

1,426,984.

Specification of Letters Patent. Patented Aug. 22, 1922.

Application filed January 31, 1921. Serial No. 441,363.

To all whom it may concern:

Be it known that I, CARL C. GULDBECH, a citizen of the United States, and a resident of Beacon, Dutchess County, New York, 5 have invented certain new and useful Improvements in Driving Mechanism for Mixing Machines, of which the following is a specification.

While my invention relates to improved 10 means for driving mixing elements generally, it has been applied more specifically in connection with the driving of mixing or beating arms or blades of dough mixers employed in bakeries. One object of my invention is to provide a special arrangement 15 of driving means whereby the mixing blades may be driven at both ends of the machine; the means employed at one end being entirely dissociated from the means employed 20 at the opposite end.

A further object of my invention is to so arrange such driving mechanism that I may employ independent motors for driving a pair of bladed shafts, through the medium 25 of suitable gearing directly connected between the shaft or shafts carrying the mixing arms or blades and the motor shaft; which gearing may comprise a worm and worm wheel as the only gearing employed; 30 thereby avoiding the necessity of using a countershaft, heretofore employed, for transmitting to the opposite end of a mixing machine power applied at one end of the same.

These and other features of my invention are more fully described hereinafter, reference being had to the accompanying drawings, in which—

Figure 1, is a longitudinal sectional view 40 of one form of mixing machine and driving means therefor, within the scope of my invention.

Fig. 2, is an end elevation of the same.

Fig. 3, is a view similar to Fig. 1, showing 45 a modified arrangement of the driving mechanism.

Figure 4, is a plan view of another form of mixing machine and driving mechanism therefor within the scope of my invention;

Figure 5, is an end elevation of the structure shown in Figure 4;

Figure 6, is a view, similar to Figure 4, showing a bowl with another form of mixing mechanism with driving means therefor 55 within the scope of my invention; and

Figure 7, is an end elevation of the same.

As may be readily understood, various arrangements of the driving motors may be employed, and among the arrangements illustrated in the drawings I have shown a 60 mixing machine having a pair of mixing blades or arms arranged to rotate about a common axis; the inner mixing blade being provided with solid shaft ends or trunnions fitting within sleeve shafts or trunnions carried by the outer mixing blades, and each of said mixing blades or arms carrying a worm-wheel which is arranged to mesh with a worm on a motor shaft; the worm-wheel at one end of the machine being attached to 70 a solid shaft end or trunnion of the inner mixing blade, while the worm-wheel at the opposite end of the machine may be attached to one of the sleeve shafts or trunnions of the outer mixing blade. 75

In lieu of employing worm and worm-wheels, the motor shafts may carry pinions arranged to mesh with spur wheels carried by the respective shafts or trunnions; the motors being set in positions substantially 80 at right angles to the position they occupy when worm gearing is employed. As may be further understood, the motors may be arranged to turn the mixing blades in the same direction or in opposite directions, and the speed of one may be altered with respect to the speed of the other so as to effect any result sought to be obtained in the mixing of material under treatment. If desired, the motors may be of different capacity. 85

In another arrangement, I may provide two sets of mixing arms or blades carried by shafts mounted upon independent axes; the same being geared together and the gearing 95 at each end of the machine being driven by an independent motor. These mixing blades may be driven in either direction as desired, but it will be understood, of course, that while the movement of one set of mixing blades or arms may be at the same speed or at a different speed with respect to the other, the time relation must be such that there will be no interference of one blade or arm or of one set of blades or arms with the other. In such arrangement, I may employ two sets of double mixing blades, or one double blade and one single blade. 100

In another arrangement, I may provide a single or double beater carried by a single 110 shaft adapted to bearings at opposite ends of the mixing bowl; each end of said shaft

carrying a worm wheel meshing with a worm driven by an independent motor. In the arrangement just described, it will be understood that the motive force necessary to drive the mixing arms or blades is from a single point may be halved in utilizing a pair of motors as the driving elements, and that I may employ spur gearing in lieu of worm gearing.

10 By the use of independent motors at opposite ends of the blades of a mixing machine in the manner described, the torque is effected gradually and in the same ratio at each end of the machine; thereby avoiding the twisting strain commonly occurring when power is applied at one end only of a shaft. A further advantage is the great leverage obtained by the employment of a worm as the transmitting medium and when 15 employed such worm is preferably provided with multiple threads in order to increase the speed transmitted to the worm wheel. A still further advantage lies in the fact that the motor being a freely rotatable element in a magnetic field, it may be halted temporarily under the severe strain of heavy duty without breaking or dislocating the power transmitting elements.

20 In the form of structure illustrated in Figs. 1 and 2, 1 represents a suitable mixing bowl of any desired type, within which may be disposed, as illustrated in the present instance, two sets of mixing blades or arms 2 and 3; the mixing blades 2, in the 25 present arrangement, being arranged to rotate on the same axis as the mixing blades 3, and being disposed within the same. The mixing blades or arms 2 may be carried by suitable end bars 4, having projecting members 5, constituting trunnions adapted to suitable bearings. The mixing blades or arms 3 may be carried by end bars 6, having hollow trunnions 7; the trunnions 5 being disposed within the hollow trunnions 7, and the latter being adapted to suitable 30 bearings 8 in end supports or standards 9.

At one end of the mixing bowl a worm-wheel 10 is attached to one of the solid trunnions 5, and at the opposite end of the bowl 50 a worm-wheel 11, similar in size to the wheel 10, may be attached to one of the hollow trunnions 7. Suitably journaled in bearings 12, which may be carried by the end standards 9, are shafts 13 and 14, carrying 55 worms 15 and 16, having multiple threads, three or four, as the case may be, which mesh with the worm-wheels 10 and 11, and these shafts 13 and 14 are operatively connected with motors 17 and 18, whereby said 60 worms 15 and 16 may be directly driven thereby and impart their movement to the worm wheels 10 and 11 for transmission to the mixing blades or arms 2 and 3.

In the form of structure illustrated in 65 Figs. 1 and 2, I preferably provide motors

of different size so that when running at full speed, one set of mixing blades or arms may move at a greater rate than the other. If desired, however, the respective sets of blades or arms may be driven at the same 70 speed. These mixing blades or arms may move in the same direction, in which case the motors will be moving in the opposite direction, or said blades or arms may move in opposite directions, in which case the 75 motors will be moving in the same direction. In lieu of changing the direction of movement of the motor armatures, I may employ any suitable form of reversible clutches between said motors and shafts; such 80 clutches being diagrammatically illustrated at 19, and these shafts 13 and 14 may also be provided with suitable couplings, indicated at 20.

In the structure shown in Fig. 3, which 85 may be of the same type as that shown in Figs. 1 and 2, I have shown the use of spur gearing between the motors and the shafts carrying the mixing blades or arms; said shafts or trunnions 5 and 7, respectively, being provided with spur wheels 21 and 22, meshing with driving pinions 23 and 24 carried by motor shafts 13^a and 14^a, driven by 90 motors 17^a and 18^a, which may differ in size; the structure in other respects being substantially similar to that shown in Figs. 1 and 2. 95

In the form of structure shown in Figures 4 and 5, two sets of mixing blades or arms 2^a and 3^a are shown, which may be carried by independent shafts 5^a and 7^a, suitably journaled in the end walls of the mixing bowl and being disposed in the same horizontal plane. In the present instance, the bowl 1^a is shown as equipped with double and single mixing blades; the latter 3^a, being arranged 100 to be driven at a speed twice that of the double mixing blade 2^a and being so set that the single blade will properly pass the arms of the double blade during their rotation. The shafts 5^a and 7^a, carrying these 105 mixing blades have gear wheels 25 and 26, at the respective ends of the structure. 110

These driving pinions 27 may be mounted on short shafts 28, journaled in suitable 115 bearings 29, carried by end supports 9^b; such shafts 28 also serving as the pivots upon which the bowl may be turned when it is desired to dump the contents of the same. These shafts 28 also carry worm-shafts 30, to which power may be applied by worms 15^b and 16^b, mounted on shafts 13^b and 14^b, 120 driven by motors 17^b and 18^b. In this arrangement, the motors may be of the same size. As may be readily understood, the motors for driving the mixing elements in this 125 form of structure may be arranged in the manner illustrated in Figure 3, and the power applied by spur gearing, as indicated thereby.

In Figures 6 and 7, I have shown a form 130

of structure in which two sets of double mixing elements may be employed, each of which may comprise pairs of arms or blades 2° and 3°, carried by end bars 4° and 6°, mounted on independent shafts 5° and 7°. These shafts carry worm wheels 10° and 11° at their respective ends, and the worm-wheels may be driven by right and left hand worms 15° and 15° driven by motors 17° and 18°. In this arrangement I may provide the shafts 5° and 7° carrying the worm-wheels with couplings 31 and 32, so that these shafts may be disconnected when it is desired to dump the mixing bowl; the latter carrying short shafts or trunnions 33 at its ends, which may be journaled at 34 in the end supports 9°, and upon which the bowl may be turned to dump its contents when said shafts 5° and 7° are disconnected at their respective couplings.

It will also be understood that the types of mixing machines illustrated in Figures 4, 5, 6 and 7, in which pairs of motors, one at each end of the machine, are employed as the driving means for pairs of shafts, may have the motion of the latter transmitted through the medium of spur gearing in a manner substantially like that illustrated in Figure 3; necessary changes being made to operatively connect the mixing elements and the motors through such form of gearing.

I claim:

1. The combination, with the bowl of a mixing machine, of a pair of bladed mixing elements disposed within said bowl and rotatable about a common axis, rotatably driven supports for said mixing elements, a motor disposed at one end of the machine for driving one of said mixing elements, gearing interposed between said motor and the rotatable support for said mixing element, a motor disposed at the opposite end of the machine for driving the other mixing element, and gearing interposed between said motor and the support of said second mixing element.

2. The combination, with the bowl of a mixing machine, of a pair of bladed mixing elements disposed within said bowl and rotatable about a common axis, rotatably driven supports or shafts for said mixing elements, a motor disposed at one end of the machine for driving one of said mixing

elements, worm gearing interposed between said motor and the rotatable support or shaft for said mixing element, a motor disposed at the opposite end of the machine for driving the other mixing element, and worm gearing interposed between said motor and the shaft or support of said second mixing element.

3. The combination, in a mixing machine, of a mixing bowl, a pair of bladed mixing elements disposed therein and rotatable about a common axis, rotatably driven shafts or supports for said mixing elements, a motor disposed at one end of the machine for driving one of said mixing elements, and a motor at the opposite end of the machine for driving the other mixing element; said motors being directly geared to the shafts or supports of said mixing elements.

4. The combination, in a mixing machine, of a mixing bowl, a pair of bladed mixing elements disposed therein, shafts for said mixing elements, a motor disposed at one end of the machine, gearing interposed between said motor and one of said shafts, a motor disposed at the opposite end of the machine, and gearing interposed between said motor and the second shaft; said motors being independent of each other and independently geared to the respective shafts.

5. The combination, with the bowl of a mixing machine, of a pair of shafts, independent sets of mixing elements carried by said shafts for operation within said mixing bowl, independent motors at opposite ends of said machine, and worm gearing operatively connected between said motors and shafts for transmitting movement of the former to the latter.

6. The combination, in a mixing machine, of a mixing bowl, a pair of mixing elements disposed therein and rotatable about a common axis, a motor disposed at one end of the machine for driving one of said mixing elements, a motor disposed at the opposite end of the machine for driving the other mixing element, and worm gearing for transmitting the movement of said motors to said mixing elements; the worm elements of said gearing having multiple threads.

In witness whereof I have signed this specification.

CARL C. GULDBECH.
